UNITED STATES PATENT OFFICE.

ERNEST L. FARROW, OF CLEVELAND HEIGHTS, OHIO; PAULINE FARROW ADMINISTRATRIX OF SAID ERNEST L. FARROW, DECEASED.

FLEXIBLE CORD OR STRIP PUZZLE.

Application filed July 19, 1927. Serial No. 206,902.

My invention relates to games or puzzles, and my object is to provide a new and interesting game or puzzle of simple form and structure made of or comprising separate thin sheets of material, such as paper or flexible cardboard, formed and fastened together in a unique way to make their detachment puzzling and difficult. The separate sheets or pieces are preferably printed, decorated and embellished, or cut to desired patterns, to produce an attractive design or picture when the sheets or pieces are fastened together, and the invention permits the making of a composite picture or design. That is to say, one element of the picture may form a part of one sheet or piece, and the additional elements of the picture may be parts of the other sheets or pieces, the complete picture or design being only made when the several sheets or pieces are interlocked together. The separation of the sheets or pieces is also made more puzzling by making the locking piece an essential part of the design or picture.

In the accompanying drawings, Fig. 1 is a front elevation of a game or puzzle made in three pieces constructed according to my invention, and Fig. 2 is a sectional view thereof on line 2—2 of Fig. 1. Fig. 3 is a rear elevation of the assembly shown in Fig. 1. Fig. 4 is an elevation of the single piece representing the hat in Fig. 1, and Fig. 5 is an elevation of the locking piece representing the bow for the band delineated on the hat. Fig. 6 is a front elevation of a modified form of the invention, the separate locking piece being in the form of spectacles for the face of the man delineated on the disk. Fig. 7 is a front elevation of a further modification, the locking piece itself forming a complete picture or design fixed in relief to the other sheets or pieces. Figs. 8, 9, and 10, are sectional views of the three sheets or pieces separated, on line 8—8 of Fig. 7. Fig. 11 is a front elevation of a four piece game or puzzle constructed according to my invention, in which one piece is made of a flexible string or cord, and Fig. 12 is a similar front elevation thereof, the slotted backing sheet being omitted as when detached. Fig. 13 is a front elevation, and Fig. 14 a sectional view, of a further modification of the invention comprising a string and a series of disks, and Figs. 15, 16, and 17, are similar views rep-

resenting still other modifications comprising strings and locking disks.

Referring to Figs. 1 to 3, the game or puzzle delineated comprises a thin flat sheet A of paper or cardboard having printed or lithographed on one face thereof a picture of the head of a young man. This sheet is slotted vertically on parallel lines 2—2 to provide a narrow flexible section or part 3 which for convenience of description may be termed a foldable loop inasmuch as its opposite ends are integrally united with the body of sheet A and because it may be flexed to form a loop when the sheet itself is flexed or bowed in an opposite direction. Superposed upon the front of sheet A is a second thin flat sheet B of paper or flexible cardboard in the shape of a hat having a downwardly bent brim and marked or printed as having a hat band 4. Sheet B has a square or rectangular opening 5 in the area designated as hat band 4, and this opening is of substantially the same size transversely as loop 3 in sheet A. When sheet B is placed flat upon sheet A with opening 5 opposite loop 3, only a small area of the loop is exposed. By doubling the loop, an operation also requiring doubling or buckling of sheet A, it is possible to project the loop through opening 5. Preferably at least one of the sheets is thin and easy to tear, and to avoid tearing of the loop the pieces must be handled with care and understanding. Briefly, attempts by unskilled or inexperienced persons to fold or unfold the loop is rendered difficult, and when a third piece C is inserted and locked in place between loop 3 and the outer face of the superposed sheet or piece B, with the loop drawn substantially flat as appears in Figs. 1 and 2, the detachment of the pieces is not obvious, especially when the locking piece C is formed with enlarged ends or extremities 6—6. In Fig. 1, these enlarged ends 6—6 represent the flaring ends of a bow or tie for hat band 4, and an illusion is presented which plays a part in the solving of the puzzle or the problem of separating the three pieces which appear to be inseparably locked together, or so locked that separation seems nearly impossible without tearing one of the pieces. The union of the three or more pieces in the way described to form a complete picture or design only when they are assembled and locked together, is also a feature of novelty and utility in a game or puzzle of this kind. A man

with a removable hat is only one exemplification of such a device. Thus in Fig. 6 I show three thin flat pieces A', B', and C', united together in the same or a corresponding manner, the picture in this case being that of the face of a man wearing large goggles or spectacles, which present a problem for removal. In this case the piece C' is perforated or provided with round openings 7—7 in its enlarged ends 6'—6'. Piece B' is shown as a round flat disk bearing the imprint of a man's face, but this piece may be stamped or cut to correspond to the outline of the face. A further carrying forward of the invention is made in Fig. 7, which comprises three separate sheets A'', B'', and C'', the latter sheet having its central area cut away in part and formed with a narrow tongue 9 having an enlargement 10 at its free end which in the present instance represents the head of an animal on a relatively long neck. In all these forms of the invention, the three sheets are thin, flat and flexible and adapted to be secured face to face in close union. The larger or main sheet may also bear any suitable printing and advertising matter, and as all the pieces may be made of paper the article may be made very cheaply and used extensively for advertising purposes. To indicate its wide range of advertising use, such games or puzzles have been made and sold in connection with automobile tires, one sheet representing a tire secured by a locking piece to the face of a second sheet portraying the rear of an automobile. Another form pictures a person wearing a bow tie; and another a dog with a bone in its mouth.

The modified form of the invention shown in Figs. 11 and 12, sheet 2 of the drawings, consists of four pieces instead of three pieces, the fourth piece being a string or cord D fastened at one end to sheet B''' and having a locking piece C''' fastened to its opposite end. The main sheet A''' is cut out to provide a horizontally extending loop portion 3, and sheet B''' contains the rectangular opening 5. Locking is effected when the string or cord D passes through the loop in front of sheet B''', the locking piece C''' being larger than opening 5. As delineated the string represents a fish line suspended from a fish pole in the hands of a fisherman, and the locking piece C''' is in the form of a fish.

In Figs. 13 and 14, I show a plain sheet of paper A⁴ having a loop 3 formed therein, together with a round flat disk B⁴ having a square opening 5 at its center. Two strings or cords E and F are threaded through the loop and through two perforated locking pieces G and H. The opposite ends of the strings or cords are secured permanently to base sheet A⁴. The puzzle or problem in this form of the invention is to reverse the position of the small disks or pieces G and H without detaching the strings.

In Figs. 15, 16 and 17, I show a base sheet A⁵ having a loop 3 at its center, together with a square sheet K having an opening 5 at its center through which loop 3 may be doubled, and the locking of the sheets together is effected by a string I having the form of a loop and fastened to base sheet A⁵. A perforated disk or piece J is threaded upon the string, and the problem is to slide or shift the disk or piece J to the opposite side of the square piece K notwithstanding that the string is looped around loop 3 in base sheet A⁵.

What I claim is:

1. A game or puzzle, comprising a flexible sheet slotted on adjoining parallel lines to form a narrow flexible portion and loop, a thin flat piece having a square opening with sides about equal in length to the width of said loop and adapted to expose a part of said loop when said piece is superposed upon said sheet, and a tie member adapted to interlock with said loop and to secure said sheet and piece non-rotatably but detachably together. 80

2. A game or puzzle, comprising a thin sheet of flexible material having parallel incisions which will permit a part of said sheet to be formed into a loop when the sheet is flexed, a thin flat piece having a square opening with sides about equal in length to the width of said loop and adapted to receive the said loop, and a tie member adapted to slip through said loop having enlargements spaced the width of said loop from each other and adapted to lock said sheet and piece non-rotatably together. 90

3. A game or puzzle, comprising a base sheet of flexible material slotted on parallel lines to permit a loop to be developed by flexing the sheet, said sheet bearing a picture; a thin flat piece having a square opening adapted to receive said loop, the sides of said opening being about equal to the width of said loop and said piece portraying a part of the picture on said sheet; and a tie member interlocking said sheet and piece tightly and detachably together. 105

4. A game or puzzle, comprising a base sheet incised to permit a loop to be developed therefrom, a separate flat piece having an opening adapted to receive said loop, a string connected to said base sheet and passing around said loop, and a perforated piece sleeved upon said string between said loop and the point of connection of said string with said base sheet. 115

5. A game or puzzle, comprising a flexible sheet incised to permit a loop to be developed therefrom, a flat piece having an opening adapted to receive said loop, a pair of strings affixed at their opposite ends to said sheet and sleeved through said loop, and a pair of perforated disks sleeved upon said strings. 120

In testimony whereof I affix my signature.
ERNEST L. FARROW.
